UNITED STATES PATENT OFFICE.

MICHAEL F. QUIGLEY, OF PORT RICHMOND, NEW YORK.

DESIGN FOR A HAIR-PIN.

49,752.

Specification for Design.

Patented Oct. 10, 1916.

Application filed July 1, 1916. Serial No. 107,198. Term of patent 14 years.

To all whom it may concern:

Be it known that I, MICHAEL F. QUIGLEY, a citizen of the United States, residing at Port Richmond, in the county of Richmond and State of New York, have invented a new, original, and ornamental Design for a Hair-Pin, of which the following is a specification, reference being had to the accompanying drawing, forming part thereof.

In the drawing, Figure 1 is a side elevation of a hair pin embodying my design, and Fig. 2 is a view at rightangles to Fig. 1.

I claim:

The ornamental design for a hair pin, as shown.

MICHAEL F. QUIGLEY.

Witnesses:

WILLIAM K. DOOLEY,
FRANKLIN V. FOGGIN.
